US00D587078S

(12) **United States Design Patent**
Garman

(10) **Patent No.:** **US D587,078 S**
(45) **Date of Patent:** **** Feb. 24, 2009**

(54) **CAN OPENER**

(75) Inventor: **Michael Garman**, Midlothian, VA (US)

(73) Assignee: **Hamilton Beach Brands, Inc.**, Glen Allen, VA (US)

(**) Term: **14 Years**

(21) Appl. No.: **29/299,816**

(22) Filed: **Jan. 4, 2008**

(51) **LOC (9) Cl. 07-99**

(52) **U.S. Cl. D8/36**

(58) **Field of Classification Search** D8/16-19, D8/21, 27, 33-43, 88, 105, 300, 307; D21/301, D21/385, 386, 388; 7/113, 151-156; 30/400-410, 30/416-430, 433, 434, 443, 450; 81/3.07, 81/3.09, 3.27, 3.4, 3.55

See application file for complete search history.
